DISPLAY BOX

Samuel Braun, Rye, N.Y., assignor to B. C. N. Design Products, Inc., Long Island, N.Y., a corporation of New York

Filed Sept. 27, 1965, Ser. No. 87,162

Term of patent 14 years

(Cl. D58—12.7)

FIG. 1

FIG.5

FIG. 1 is a three-quarter front perspective view taken from the front and above of the display box showing my new design, with the lid and movable front wall section in closed position;

FIG. 2 is a three-quarter perspective view taken from the rear and below of the display box;

FIG. 3 is a view similar to FIG. 1, but on an enlarged scale and with the lid and movable front wall section being shown in open position; and

FIGS. 4 and 5 are fragmentary cross-sectional views on a further enlarged scale taken along the lines 4—4 and 5—5 respectively of FIG. 3.

The dominant features of my design reside in the portion shown in full lines.

I claim:

The ornamental design for a display box, as shown and described.
